DESIGN FOR A SEMITRAILER TANK BODY

Edward H. Gill, Kansas City, Mo., assignor to
Andrew A. Kramer, Kansas City, Mo.

Application April 22, 1937, Serial No. 68,933

Term of patent 14 years

To all whom it may concern:

Be it known that I, Edward H. Gill, a citizen of the United States, residing at Kansas City, in the county of Jackson and State of Missouri, have invented a new, original, and ornamental Design for a Semitrailer Tank Body, of which the following is a specification, reference being had to the accompanying drawing, forming a part thereof.

In the drawing:

Fig. 1 is a side elevation of a semitrailer tank body showing my new design.

Fig. 2 is a top plan view thereof, and
Fig. 3 is a rear elevation thereof.

I claim:

The ornamental design for a semitrailer tank body substantially as shown.

EDWARD H. GILL.
